KNIFE JOINTER

Julius B. Sevey, Swink, Colo., assignor to Holly Sugar Corporation, Colorado Springs, Colo., a corporation of New York

Application November 12, 1943, Serial No. 510,058

9 Claims. (Cl. 51—92)

This invention relates to improvements in knife jointers and has reference more particularly to a machine designed for use in connection with the reconditioning and sharpening of knives that are employed in connection with beet slicing machines.

In sugar beet factories, the beets, after being carefully cleaned and washed, are directed to a slicing machine where they are cut into long narrow strips preparatory to extracting the sugar in the diffusion battery. Such slicing machines are provided with a large number of transversely fluted knives that must be kept in good order and which are frequently dulled and otherwise damaged by the presence of solid material, such as small rocks that accidentally enter the slicing machine.

Machines for use in reconditioning and sharpening such slicer knives are referred to as knife jointers and must be carefully constructed to obtain the best operation.

It is the object of this invention to produce a machine of the type referred to, which shall be of a simple and substantial construction and which shall be provided with means for conveniently clamping a knife in place therein and for moving it transversely of a grinding wheel.

It is the further object of this invention to produce a machine of the type described in which the knife clamping means comprises two relatively movable clamping jaws, one of which is provided with a shoulder for positioning the knife in a predetermined relation thereto, and the other of which is provided with means for engaging the knife and urging it against the shoulder and simultaneously therewith clamping it in position.

Another object of this invention is to produce a machine of this type in which the transverse angularity of the cut made by the wheel can be adjusted to obtain the angular relationship desired.

A further object of the invention is to produce a machine of this type in which the blade clamping means can be raised so as to expose the ground edge for inspection during the jointing operation.

A still further object of the invention is to produce a machine in which the movable parts associated with the knife clamping and guiding means shall be protected against abrasives separated from the grinding wheel to the end that excessive wear is prevented.

Another object of the invention is to produce a machine in which the knife clamping and guiding means can be adjusted as a unit towards and

from the axis of the grinding wheel so as to adjust for different sized grinding wheels and to compensate for wear thereof.

The above and other objects that may become apparent as this description proceeds are attained by means of a construction and an arrangement of parts that will now be described in detail and for this purpose reference will be had to the accompanying drawings in which the invention has been illustrated in its preferred form, and in which:

Figure 1 shows a front elevation of the machine, a portion being broken away to disclose the position of the motor;

Figure 2 is a top plan view of the machine shown in Figure 1;

Figure 3 is a section taken on line 3—3, Figure 1;

Figure 4 is a section taken on line 4—4, Figure 2;

Figure 5 is a section taken on line 5—5, Figure 2;

Figure 6 is a perspective view showing the lower clamping jaw;

Figure 7 is a perspective view of the carriage plate; and

Figure 8 is a view showing a slight modification.

In the drawings reference numeral 10 designates a supporting surface, such as a floor on which the machine rests. The machine consists of a frame or a cabinet-like structure which has been shown in a more or less diagrammatic manner and which has a back 11, sides 12 and doors 13, which are connected by means of hinges 14 with the door frame 15. The top of the cabinet or frame is formed by a plate 16. The several parts of the cabinet or frame are connected by angle irons 17, or by other suitable means.

Since the invention does not relate to the support or cabinet, the latter has been shown and described in a more or less diagrammatic manner.

Supported on the top plate 16 is a carriage adjusting plate 17' which is adjustably connected with plate 16 by means of four bolts 18, which pass through elongated openings 19 in plate 17'. Bolts 18 are kept from turning by means of a rod 20 that projects through holes in the heads of the bolts as shown more particularly in Figure 4. Secured to the top plate 16 are two spaced bearings 21 in which a shaft 22 is mounted for rotation. The construction of bearings 21 has not been shown because they are of a standard construction and form no part of this invention, except as they constitute an element of the combination. Shaft 22 is rotatable in the bearings, but

held against longitudinal movement therein by the particular construction of the ball bearings employed. Secured to the outer end of shaft 22, is a small rotatable brush 23, and secured to the other end is a grinding wheel 24. Plate 16 is provided with an opening 25, through which the lower portion of the grinding wheel extends. Positioned below the grinding wheel is an inclined plate 26 that forms the bottom of the channel through which the material removed from wheel and the knives that are being sharpened, can pass to the outside of the cabinet. A motor 27 is supported on a plate 28 one end of which is pivoted at 29 to an angle iron bracket 30 and the other end of which is connected by a link 31 to a nut 32 that is rotatably connected with a screw 33. This screw is held against longitudinal adjustment by means of collar 34 and moves in bearings in plates 35 that, in turn, are secured to the cabinet by means of angle iron brackets 36. By turning the screw 33, the motor supporting plate can be tilted, thereby adjusting the distance between the center of the motor shaft and the center of shaft 22 for the purpose of adjusting the tension of the belt 37. In the drawing belt 37 has been shown as a flat belt for convenience in illustrating, in the actual construction however, a multi-V-type belt drive is employed. The motor is connected with a source of electric energy and controlled by the usual means which have not been illustrated because they are of conventional construction. The motor rotates in a counter-clockwise direction when viewed as in Figure 3 and this imparts to the grinding wheel 24, a rotation in the same direction, whereby the surface in contact with the knife to be sharpened moves downwardly.

Secured to the upper surface of the carriage adjusting plate 17, are two bearings that have been designated by reference numerals 38. These are positioned in axial alignment and secured to the carriage plate by means of tap screws 39. A shaft 40 is slidably mounted in bearings 38 and is movable in the direction of its axes and is also rotatable in the bearings. Each bearing 38 is provided in its outer surface with a threaded opening 41 in which the inner end of the pipe 42 is threaded. Caps 43 close the outer ends of pipes 42. The purpose of the tubular extension comprising pipe 42 is to protect shaft 40 from abrasive material and from dust and dirt that is invariably found around this type machine. In the form illustrated, the carriage plate 44 is secured to the upper surface of shaft 40 by means of bolts 45. This plate is provided at its outer end with a notch 46 from which a hole 47 extends inwardly in the manner shown in Figure 7. Intersecting the hole 47 is an opening 48 in which the nut 49 is positioned as shown in Figure 4. Secured to the carriage plate 44 are two bearings 50 which have openings for the reception of the trunnions 51 that project from the ends of the eccentric adjusting bar 52. Bearings 50 are split as indicated by reference numeral 53 in Figure 3, and are provided with screws 54 by means of which the trunnions 51 may be clamped and held against rotation. The inner end of carriage plate 44 rests on the upper surface of the eccentric 53, and it is evident that by turning the eccentric about the axis of its trunnions, the carriage plate can be adjusted vertically with respect to the top of plate 16. During this adjustment, plate 44 will naturally rotate slightly about the axis of shaft 40. Supported on plate 44 and movable longitudinally thereon is a knife

clamping plate or lower jaw which has been designated by reference numeral 55. The jaw 55 is provided with four-threaded openings 56 for the reception of bolts 57 that extend through the elongated openings 58 in carriage plate 44. It will thus be seen that the lower clamping jaw can be moved longitudinally with respect to the carriage plate and this movement is effected and controlled by means of a screw 59 that cooperates with the nut 49. Plate 55 is provided at its outer end with a downwardly extending portion 60 that has an opening 61 through which a portion of bolt 59 passes. This bolt is provided with a collar 62 on its outer end with adjustable lock-nuts 63. A handle 64 serves as a means for rotating this screw for the purpose of moving plate 55 with respect to the carriage plate 44. The operation of this adjusting means is clearly apparent from Figure 4. The lower clamping jaw 55 is provided at its inner end with a depressed area that terminates in a transversely extending shoulder 65 which serves as a positioning means for the slicer knife 66. The jaw 55 is also provided with a depression 67 in which a helical screw 68 is positioned. It is also provided with a threaded opening 69 for the reception of the threaded lower end of the clamping screw 70. The upper plate of jaw 55 is further provided with an elongated depressed area 71 to which reference will hereinafter be made. An upper knife clamping jaw or knife holding plate 72 is provided with a tubular hub 73 through which the clamping screw 70 extends. From Figure 4 it will be seen that the opening in hub 73 is larger than the diameter of the clamping screw 70 so that this clamping plate may move longitudinally with respect to the lower jaw for a purpose which will hereinafter appear. A nut 74 cooperates with the upper threaded end of screw 70 to move plate 72 towards the lower clamping jaw 55. The upper knife clamping jaw or plate 72 is provided on its lower surface with a downwardly extending pin 75 while the lower end extends into the depressed area 71 and serves as a fulcrum about which this jaw or knife clamping plate turns. The helical spring 68 tends to separate the plates and when the nut 74 is rotated in a direction to move it upwardly on screw 70, the upper jaw or knife clamping plate will also move upwardly. The inner end of plate 72 is provided with two downwardly extending conical pins 76 that engage the upper surface of the knife 66 during the clamping and holding operation.

Attention is now directed to the fact that the upper surface of the hub 73 is inclined with respect to the axis of the opening therein and this inclined surface has been designated by reference numeral 77. A wedge shaped washer 78 is positioned between the nut 74 and the inclined surface 77, and therefore whenever the nut 74 is moved downwardly so as to clamp the knife 66, the force exerted will be resolved into two components, one of which extends downwardly and the other of which extends rearwardly and tends to move the plate towards the left when viewed as in Figure 4. This last force moves the knife against the shoulder 65 and serves to position it in a predetermined manner without any special effort on the part of the operator. This feature of the construction is of considerable importance in a knife jointer of this type because it is necessary that the cutting edge of the knife shall always bear a predetermined angular relation to the back thereof so as to be sure that it will function properly when positioned in the slic-

ing machine. At this point attention is directed to the fact that the shoulder 65 must be parallel with the axis of shaft 40; or, in other words, parallel with the direction in which the carriage moves during the grinding operation.

In the drawings, the axis of shaft 40 has been shown parallel with the axis of shaft 22. This is always a desirable arrangement, but not essential to proper operation, as the machine will function properly even if these two shafts are not parallel. In the same manner it is not absolutely essential that the axis of the eccentric 62 shall be parallel with the axis of shaft 40, but it is desirable and when an eccentric adjusting element like that shown is used absolute accuracy requires that this element shall be parallel with shaft 40. The eccentric means for adjusting the distance of the carriage plate from the top of plate 17 can, of course, be replaced by any suitable mechanical equivalent thereof and the eccentric as shown is merely representative of means for this purpose.

In the construction illustrated, shaft 42 moves longitudinally in bearings 38 but attention is called to the fact that this shaft may be stationary with respect to the bearing and the carriage slideable on the shaft. In this case the carriage plate 44 is provided on its under surface with a bearing 19 as shown in Figure 8.

Since grinding machines of this kind liberate a lot of abrading dust and steel particles, it is necessary that shaft 40 be protected and for this purpose flexible sleeves 80 are provided which extend from the bearings 38 to a part of the shaft adjacent the carriage plate. When a construction like that indicated in Figure 8 is used, these sleeves extend from the bearing 19 to points adjacent bearings 38, the function in both instances being to prevent abradant dust from collecting on the shaft and interfering with the free movement of the carriage.

During the jointing or grinding operation, it is sometimes desirable to inspect the edge of the knife being ground and with this construction the carriage can be tilted in a counterclockwise direction when viewed as in Figure 4, bringing the knife into the dotted line position shown.

When different sized wheels are applied to the shaft 22, the carriage assembly can be adjusted as a unit by shifting the plate 17 with respect to the top plate 16 and then clamping these two plates in adjusted position by the bolts 18. The ordinary adjustment of the knife during the grinding operation is effected by rotating the handle 64 and the screw with which it is connected. In the actual construction, the grinding wheel is provided with a cover like that indicated by broken lines in Figure 3 and designated by reference numeral 81.

With the construction illustrated, the carriage is moved manually for the purpose of moving the knife across the grinding wheel. Suitable stops like those designated by reference numeral 82 in Figure 2 may be provided, if desired.

Having described the invention what is claimed as new is:

1. A slicing knife jointer comprising a base, a grinding wheel mounted thereon for rotation about an axis, a shaft secured to the base in spaced relation to the grinding wheel axis, means carried by the shaft for clamping and holding a slicing knife blade, said clamping means being movable in the direction of the axis of the shaft and mounted for limited rotary movement about

the axis of the shaft, means for moving the clamping means towards and away from the axis of the shaft, means for supporting the clamping means, said means comprising a bar positioned between the shaft and the grinding wheel underneath the corresponding end of the clamping means, the upper surface of the bar being parallel with the axis of the shaft, means for adjusting the bar vertically said bar being stationary relative to the base, the clamping means being movable relative to the bar in the direction of its length, and means for turning the grinding wheel so that the surface facing the supporting bar moves downwardly.

15. 2. A slicing knife jointer comprising a base, a grinding wheel mounted thereon for rotation about an axis, a shaft secured to the base and spaced from the wheel axis, means carried by the shaft for clamping and holding a slicing knife blade, said means being movable in the direction of the axis of the shaft and mounted for limited rotary movement about the shaft axis, said clamping means comprising two relatively movable jaws, and means for moving them towards each other into blade clamping position, means for moving the jaws towards and away from the axis of the shaft, means for supporting the clamping means comprising a bar positioned between the shaft and the grinding wheel underneath the corresponding end of the clamping means, said bar being mounted for rotation, the outer surface of the bar having longitudinal elements spaced different distances from its axis of rotation, means for clamping the bar in rotatably adjusted position, and means for rotating the grinding wheel in such a direction that the surface facing the clamping device moves downwardly.

30. 3. A slicing knife jointer comprising a base, a grinding wheel mounted thereon for rotation about an axis, a shaft secured to the base, spaced from the wheel axis and substantially parallel therewith, means carried by the shaft for clamping and holding a slicing knife blade, said means being movable in the direction of the axis of the shaft and mounted for limited rotary movement about the shaft axis, said clamping means comprising two relatively movable jaws and means for moving them towards each other into blade clamping position, means for moving the jaws towards and away from the axis of the shaft, means for supporting the clamping means comprising a bar positioned between the shaft and the grinding wheel underneath the corresponding end of the clamping means, said bar being substantially parallel with the shaft, means for adjusting the upper surface of the bar in a vertical direction and for clamping it in vertically adjusted position, and means for rotating the grinding wheel in such a direction that the surface facing the clamping device moves downwardly.

35. 4. A slicing knife jointer comprising a base, a grinding wheel mounted thereon for rotation about an axis, a shaft secured to the base and spaced from the wheel axis, means carried by the shaft for clamping and holding a slicing knife blade, said means being movable in the direction of the axis of the shaft and mounted for limited rotary movement about the shaft axis, said clamping means comprising two relatively movable jaws, and means for moving them towards each other into blade clamping position, means for moving the jaws towards and away from the axis of the shaft, means for supporting the clamping

means comprising a bar positioned between the shaft and the grinding wheel underneath the corresponding end of the clamping means, said bar being mounted for rotation, the outer surface of the bar being eccentric with respect to its axis of rotation, means for clamping the bar in rotatably adjusted position, and means for rotating the grinding wheel in such a direction that the surface facing the clamping device moves downwardly.

5. A slicing knife jointer comprising a base, a grinding wheel mounted thereon for rotation about an axis, a shaft secured to the base, spaced from the wheel axis and substantially parallel therewith, means carried by the shaft for holding and clamping a slicing knife blade, said means being movable in the direction of the axis of the shaft and mounted for limited rotary movement about the shaft axis, said clamping means comprising two relatively movable jaws, means for moving the jaws towards each other into blade clamping position and for simultaneously moving the jaws relative to each other in a longitudinal direction, means for moving the jaws towards and away from the axis of the shaft, means for supporting the clamping means comprising a bar positioned between the shaft and the grinding wheel underneath the corresponding end of the clamping means, said bar being mounted for rotation, the outer surface of the bar having longitudinal elements spaced different distances from its axis of rotation, means for clamping the bar in rotatably adjusted position, and means for rotating the grinding wheel in such a direction that the surface facing the clamping device moves downwardly.

6. A slicing knife jointer comprising a base, a grinding wheel mounted thereon for rotation about an axis, two spaced bearings supported by the base, a shaft mounted in the bearings for movement in the direction of its axis and for rotary movement about its axis, the shaft being spaced from the grinding wheel axis and substantially parallel therewith, a support bar positioned between the shaft and the grinding wheel, the upper surface of the bar being positioned in a horizontal plane parallel with a horizontal plane containing the axis of the shaft, a knife clamping device comprising a jaw plate having one end movably connected with the shaft and the other end resting on the bar, a second jaw member positioned above the first and supported thereby, means for urging the jaws towards each other comprising a screw, a fulcrum pin positioned between the screw and the end of the lower jaw adjacent the shaft, means for urging the jaws apart comprising a compression spring positioned between the jaws on the opposite side of the screw from the fulcrum, the lower jaw having a transverse shoulder forming a positioning stop for a slicer knife, the upper jaw having spaced downwardly extending pins for engaging the upper surface of the knife, the hole in the upper jaw through which the screw passes being larger than the screw to permit the jaw to slide, and means responsive to the clamping pressure exerted by the screw for exerting a force tending to move the upper jaw in a direction to force the knife against the shoulder.

7. A slicing knife jointer comprising a base, a grinding wheel mounted thereon for rotation about an axis, two spaced bearings supported by the base, a shaft mounted in the bearings for movement in the direction of its axis and for rotary movement about its axis, the shaft being

spaced from the grinding wheel axis and substantially parallel therewith, a support bar positioned between the shaft and the grinding wheel, the upper surface of the bar being positioned in a horizontal plane parallel with a horizontal plane containing the axis of the shaft, a knife clamping device comprising a jaw plate having one end secured to the shaft and the other end resting on the bar, a second jaw member positioned above the first and supported thereby, means for urging the jaws towards each other comprising a screw, a fulcrum pin positioned between the screw and the end of the lower jaw adjacent the shaft, means for urging the jaws apart comprising a compression spring positioned between the jaws on the opposite side of the screw from the fulcrum, the lower jaw having a transverse shoulder forming a positioning stop for a slicer knife, the upper jaw having spaced downwardly extending pins for engaging the upper surface of the knife, the hole in the upper jaw through which the screw passes being larger than the screw to permit the jaw to slide and means responsive to the clamping pressure exerted by the screw for exerting a force tending to move the upper jaw in a direction to force the knife against the shoulder, said named means comprising a screw encircling hub attached to the upper surface of the upper jaw, the upper end of said hub being forwardly and downwardly inclined, and a wedge washer resting on the hub with its inclined surface in operative engagement with the upper surface of the hub whereby the force exerted by the screw will be separated into two components one of which urges the upper jaw rearwardly.

8. A slicer knife clamping and guiding assembly for use with a slicer knife jointer, comprising a plate, two axially spaced bearings secured to the upper surface thereof, a shaft having its ends positioned in the bearings, a support bar carried by the plate spaced from the shaft, a lower jaw plate having one end movably secured to the shaft and the other end resting on the support bar, the jaw plate being movable along the axis of the shaft and angularly about the shaft axis, means for moving the jaw plate transversely of the shaft, an upper jaw plate supported on the under one, means comprising a bolt for producing a force urging the jaw plates together, a fulcrum pin secured to one plate and engaging the other, the pin being positioned adjacent the shaft, means comprising a compression spring positioned between the jaw plates, on the opposite side of the bolt from the fulcrum, the lower jaw having its upper surface provided with a transverse shoulder for positioning a slicer knife, the upper jaw plate having downwardly projecting spaced pins for engaging the slicer knife, and means responsive to the clamping force exerted by the screw for producing a force tending to urge the upper jaw plate towards the shaft for moving the knife against the positioning shoulder.

9. A slicer knife clamping and guiding assembly for use with a slicer knife jointer, comprising a plate, two axially spaced bearings secured to the upper surface thereof, a shaft having its ends positioned in the bearings, a support bar carried by the plate and spaced from the shaft, means for adjusting the distance from the surface of the plate to the upper surface of the support bar, a lower jaw plate having one end secured to the shaft, and its other end resting on the support bar, means for moving said jaw plate in a direction transversely of the shaft, the jaw plate being also movable in the direction of the axis of the

shaft and angularly thereabout, an upper jaw plate supported on the lower jaw plate, a fulcrum pin secured to one jaw plate, adjacent the shaft, and engaging the other plate, a screw connected with the lower jaw plate and extending through an opening in the upper jaw plate, means comprising the screw for urging the jaw plates towards each other into knife clamping position,

means comprising a spring positioned between the plates for urging them apart, the clamping surface of one of the plates having a transversely extending knife positioning shoulder, and means comprising the clamping screw for producing a force urging the other plate in a direction facing the shoulder to position the knife thereagainst.

JULIUS B. SEVEY.
